STORM SASH AND CASEMENT WINDOW CONNECTOR

Filed Feb. 12, 1945

UNITED STATES PATENT OFFICE

2,440,223

STORM SASH AND CASEMENT WINDOW CONNECTOR

Joseph Martin, Dayton, Ohio

Application February 12, 1945, Serial No. 577,360

4 Claims. (Cl. 16—1)

1

This invention relates to storm sash for casement windows, and more particularly, to an improved means for connecting a storm sash with an outwardly opening casement window whereby the storm sash and casement window may be articulated in their operation to enable the same to be opened or closed simultaneously by movement of one or the other.

The increasing popularity of storm sash has brought with it the problem of providing a simple and efficient means for opening the storm sash simultaneously with the window in an articulated operation, in view of the difficulties involved in the necessity for first opening the casement window and then separately opening the storm window where no such articulating interconnecting linkage is employed. In cold climates it has been found very advantageous to employ storm sash for better insulation during the cold season. However, the provision of storm sash poses the problem of providing adequate ventilation in mild weather when it would be normally desired to open one or more windows having storm sash provided outwardly thereof.

When it is desired to air a room, the windows of which are provided with storm sash, it is obviously necessary not only to open the window but also to open the storm sash. However, the window sash in metal window constructions is commonly hinged for opening outwardly about a vertical axis. Since the storm sash must be located outside of the window in close proximity thereto, there is not sufficient room to effect the opening of the window independently of the storm sash. Hence it has become desirable to provide means for articulating the operation of the window and the storm sash whereby the same may be opened and closed simultaneously. This can best be done by providing connecting means between the window and the storm sash which will enable the latter to be operated for opening and closing the same by the operation of the window.

One problem that arises in connection with the provision of such connecting means involves the making of the same adjustable for application to different installations, since the initial distance between the window and the storm sash, when the same are in closed position, will vary with different installations.

Another problem involves the provision of connecting means in which there is no play between the relatively movable parts which would produce rattling of the connector means due to the effect of wind upon the window and storm sash

particularly when the same are in open position.

Still another problem involved in the provision of suitable connecting means of the type referred to relates to provisions for insuring tight closing of the storm sash automatically when the casement window itself is closed and it will be apparent that, after the window is closed, the storm sash cannot thereafter be manipulated from the inside to close it more tightly.

10 The principal object of the invention is to provide an improved, simple, and efficient means for interconnecting a casement window with a storm sash for articulated operation of the same in unison.

15 Another object of the invention is to provide a connector of rugged construction in which the movable parts have substantially no play or looseness irrespective of the relative positions which the parts may assume in their articulating operation.

20 Another object of the invention is to provide a connector having provision for longitudinal adjustability whereby the connector may be adapted to different installations in order to accommodate the connector to variations in the initial distance between the casement window and the storm sash in different installations.

25 Another object of the invention is to provide an improved connector for storm sash which is capable of producing an initial tension between the storm sash and casement window when the same are in closed position whereby to insure a tight sealing relation of the storm sash with respect to the window frame with which it engages in closed position.

30 Other objects, advantages and features of the invention will become apparent from the following detailed description taken in conjunction with the accompanying drawing in which—

35 Fig. 1 is a horizontal sectional view showing the connector device of my invention applied to a center vent outswinging casement and outswinging storm sash connected thereto, the section being taken through the casement window and storm sash and showing a portion of the wall or building containing the window opening.

40 Fig. 2 is a view similar to Fig. 1 showing my device applied to a double center vent outswinging casement and outstanding storm sash connected thereto.

45 Fig. 3 is an enlarged detail, sectional view of the hanging style and meeting rails with my device attached.

50 Fig. 4 is a perspective view of the storm sash

and window connector of the invention showing the disposition of the elements when the respective sash units connected by it are in closed positions.

Fig. 5 is a perspective view of the connector of the invention showing the disposition of the elements when the respective units connected by it are in open position.

Now referring to the drawing and describing the invention in detail, the numeral 1 designates the wall of a building provided with a window opening. Within the window opening in the wall is set the usual frame 2, to which the metal frame 3 of a fixed window section 4 is secured. The frame 3 may comprise a steel Z bar of usual and well-known construction.

An outwardly opening casement sash 5 is hinged as at 6 to the frame 3 of the fixed window section 4 to swing about vertical pivots, the casement sash 5 comprising a steel Z bar arranged to seat in overlapping relation to the frame 3 of the fixed window section 4 when the casement sash 5 is in closed position. The free edge of the sash 5 is provided with a pivoted latch 7 adapted to cooperate with the adjacent edge of the frame 3 to lock the casement sash 5 in closed position. The sash 5 may be opened and closed by means of conventional mechanism, usually comprising an operating handle operating through worm gear motion transmitting mechanism upon a lever pivoted to the window frame and to the casement sash. Such window opening and closing mechanism is not shown since it forms no part of the present invention.

The frame 3 and sash 5 have panes of glass 8 and 9 respectively set therein in the usual way by means of putty or any common expedient.

Mounted outwardly of the windows 4 and 5 on the side thereof that is exposed to the weather is a storm window comprising the fixed section 10 and a movable section 11. The fixed section 10 of the storm windows may comprise wooden frame 12 secured to the window frame 2 by fastening means 13 and in overlapped relation to the wall 1 of the building in the manner indicated to provide an adequate weather seal. The movable section 11 of the storm window comprises an outwardly swinging storm sash 14 which is hinged to the frame 12 as at 15 to swing about vertical pivots similarly to the casement sash 5. The frame 12 and sash 14 may be provided with complementary overlapping meeting edges as shown to provide adequate weather sealing engagement when the movable sash 14 is in closed position seating against the frame 12 of the fixed storm window section 10. The sash 12 and 14 will be provided with panes of glass 16 and 17 respectively secured in the respective sash by putty or any other suitable means.

For connecting the casement sash 5 to the movable storm sash 14, the novel connector means of my invention, generally indicated by the numeral 20, is provided which enables the sash 5 and 14 to move in unison when one or the other is operated to open or close the same. The connector 20, as best shown in Figs. 4 and 5, comprises a pair of attaching members or brackets 21 and 21' adapted for attachment to the storm sash 14 and casement sash 5 respectively. As illustrated, each attaching member 21 and 21' is made in the form of a U-shaped element having legs disposed in substantially parallel spaced relation, the base portion of the U-shaped element serving to join the legs thereof.

The attaching member 21 has the legs 22 and

23 disposed in substantially parallel relation and the base portion 24 of the U-shaped element joins the legs 22 and 23. The legs 22 and 23 are laterally extended at either side of the open end 5 of the U-shaped element to provide feet 25 and 26 which are adapted to bear against the sash with which the respective attaching member is associated, and the feet 25 and 26 are provided with apertures 27 and 28 respectively for receiving attaching elements such as screws 29 for securing the attaching member 21 to the sash. The attaching members 21 and 21' are identical in construction and the corresponding parts of the member 21' have been designated by primed numerals corresponding to the numerals designating like parts of attaching member 21. The base portions 24 and 24' (of the U-shaped elements forming the legs of each attaching member 21 and 21') are slotted or cut away as indicated at 30 and 30' in Figs. 4 and 5 to accommodate the link 31 for pivotal movement into the slots 30 and 30' in the condition of the connector 20 as shown in Fig. 4.

The link 31 is formed of steel or other suitable material of substantially rigid or non-yielding construction and is pivotally connected to each of the attaching members or brackets 21 and 21'. For this purpose the link 31 has a plurality of apertures 32 adjacent each end of the link, and spaced lengthwise of the link, for receiving the pivot members 33 and 33' associated with the attaching members 21 and 21' respectively. The pivot members 33 and 33' may be in the form of cotter-pins, as shown, adapted to extend through suitable apertures provided in the legs 22, 23 and 22', 23' of the respective attaching members 21 and 21' whereby to provide pivotal connections for the ends of the link 31 with the respective attaching members 21 and 21'. The apertures in the legs 22, 23 and 22', 23' for receiving the pivot members 33 and 33' are spaced from the marginal edges of the legs and in longitudinal alignment generally with the slots 30 or 30' rather than the base portions 24 or 24'.

50 Attaching members 21 and 21' are each formed of steel or other suitable material of a condition to provide a substantially rigid or non-yielding construction. The forming of the members 21 and 21' in a U-shape provides spaced legs 22 and 23 presenting inner surfaces facing one another, which inner surfaces are substantially plane and in parallel relation. The link 31 is rectangular in cross section so that its opposite sides present substantially parallel plane surfaces. One end 55 of the link 31 extends between the legs 22 and 23 of the attaching member 21 with each of the plane surfaces of that end of the link 31 in bearing relation with the inner plane surface of one of the legs 22 and 23 of the attaching member 21. Similarly the other end of the link 31 extends between the legs 22' and 23' of the attaching member 21' with each of the plane surfaces at that end of the link 31 in bearing relation with the inner plane surface of one of the legs 22' and 23' of the attaching member 21'.

This construction of the link 31 and attaching members 21 and 21' with the pivotal connection of the ends of the link with respective attaching members and the plane bearing surfaces of opposite sides of each end of the link in bearing relation with respective plane inner surfaces of the legs of the attaching members 21 and 21' provides a very rigid construction which will prevent wobbling of the link relative to the respec-

75

five attaching members 21 and 21' in any position of pivotal movement of the link 31 with respect to said attaching members 21 and 21'. This construction is very advantageous to prevent rattling of the linkage especially when the casement sash and movable storm sash are in open position.

The connector 20 of Figs 4 and 5 is secured to the casement sash 5 and movable storm sash 14 so that the pivot members 33 and 33' are vertically disposed. Fig. 4 illustrates the disposition of the elements of the connector 20 when the sash 5 and 14 connected thereby are in closed position illustrated by full lines in Figs. 1 and 2, in which condition it will be noted that the link 31 is accommodated within the slots 30 and 30' of the attaching members 21 and 21' respectively.

In operation, with the casement sash 5 and the storm sash 14 connected by means of the connector 20, the latch 7 may be swung to unlatched condition and the sash 5 and 14 swung outwardly to the dotted line position as illustrated in Figs. 1 and 2. Under such condition the link 31 has pivotal movement relative to each of the attaching members 21 and 21' so that the elements of the connector 20 may assume the disposition illustrated by Fig. 5.

The provision of a plurality of apertures 32 through the link 31 adjacent each end thereof and in spaced relation lengthwise of the link provides for adjusting the effective length of the link 31 operating between the pivot members 33 and 33', whereby the connector 20 is adaptable to different installations, since the initial distance between the sash 5 and 14, when the same are in closed position, may vary in different installations. Preferably, the effective length of the link 31 will be adjusted by inserting the pivot members 33 and 33' through the legs of their respective brackets and through apertures 32 of the link 31 such that the application of the connector to the sash 5 and 14 tends to pull the free edges of the respective sash closer together than they would normally be in their closed position if the connector 20 were not attached thereto. This adjustment places the connector 20 under tension, when the sash 5 and 14 are in closed position and the sash 5 is latched, whereby to draw the storm sash 14 more tightly against the frame 12 to insure better weather sealing relation.

I am aware that previous constructions of connectors for connecting casement sash and movable storm sash together for operation in unison have been proposed in the art. One example of such a prior art connector for this purpose comprises apertured brackets respectively secured to the storm sash and the casement sash and a link having angularly disposed ends received in the apertures of the respective brackets. Another example of prior art construction comprises fixed pivot members extending from each of the respective storm and casement sash and a linkage comprising spring biased telescoping tubular members threaded to one another, each of the tubular members being pivotally connected to one of the pivot members on the respective storm sash and casement sash. Still another example of prior art construction comprises the use of a turn buckle, the ends of which are pivotally connected respectively to the storm sash and casement sash. I make no claim to any features of such prior art constructions.

Having thus described my invention, what I

claim as new and desire to secure by Letters Patent of the United States is:

1. A connector for joining a storm sash to a casement sash, said connector comprising a pair of attaching members adapted for attachment to the inner side of a swinging storm sash and to the outer side of a swinging casement sash respectively, each of said members comprising a substantially U-shaped element providing spaced legs presenting substantially parallel plane surfaces facing one another and a base portion joining said legs, a link, each end of said link having substantially parallel plane surfaces on opposite sides of the link, and each end of said link extending between the legs of a respective attaching member with each of said end surfaces of said link in bearing relation with the plane surface of one of the legs of a respective attaching member, and detachable pivot means pivotally connecting respective ends of said link to the respective attaching members, each of said elements having the base portion thereof joining the legs slotted transversely to accommodate the link for pivotal movement thereof into said slotted portion between said legs, the slotted portions of said U-shaped elements being located at opposite sides of their respective attaching members, the attaching members being arranged with respect to the link so that when pivotally disposed with their base portions facing toward one another the unslotted base portion of one attaching member is disposed on one side of said link and the unslotted base portion of the other attaching member is disposed on the other side of said link.
2. A connection for joining a swinging storm sash to a swinging casement sash, said connector comprising a pair of attaching members adapted for attachment to the inner side of the storm sash and to the outer side of the casement sash respectively, each of said attaching members comprising a substantially U-shaped element providing spaced legs and a base portion joining said legs, a link, each end of said link extending between the legs of a respective attaching member, and detachable pivot means pivotally connecting respective ends of said link to the respective attaching members, each of said elements having the base portion thereof joining said legs slotted transversely to accommodate the link for pivotal movement thereof into said slotted portion between said legs, the transversely slotted portion of said U-shaped elements being located at opposite sides of their respective attaching members, the attaching members being arranged with respect to the link so that when pivotally disposed with their base portions facing toward one another the unslotted base portion of one attaching member is disposed on one side of said link and the unslotted base portion of the other attaching member is disposed on the other side of said link, whereby to permit pivotal movement of said attaching members in the same direction relative said link.
3. A connection for joining a swinging storm sash to a swinging casement sash, said connector comprising a pair of attaching members adapted for attachment to the inner side of the storm sash and to the outer side of the casement sash respectively, each of said attaching members comprising a substantially U-shaped element providing spaced legs and a base portion joining said legs, a link, each end of said link extending between the legs of a respective attaching member, and detachable pivot means pivotally connecting

respective ends of said link to the respective attaching members, each of said elements having the base portion thereof joining said legs slotted transversely to accommodate the link for pivotal movement thereof into said slotted portion between said legs, the transversely slotted portion of said U-shaped elements being located at opposite sides of their respective attaching members, the attaching members being arranged with respect to the link so that when pivotally disposed with their base portions facing toward one another the unslotted base portion of one attaching member is disposed on one side of said link and the unslotted base portion of the other attaching member is disposed on the other side of said link, whereby to permit pivotal movement of said attaching members in the same direction relative said link, said link having a plurality of pin receiving apertures adjacent each end of said link, said apertures being disposed in spaced relation lengthwise of said link whereby said detachable pivot means may be selectively inserted through said apertures for adjusting the effective length of said link when the respective pivot members are operatively associated with the respective attaching members.

4. A connector for joining a storm sash to a casement sash, said connector comprising a pair of attaching members adapted for attachment to the inner side of a swinging storm sash and to the outer side of a swinging casement sash respectively, each of said members comprising a substantially U-shaped element providing spaced legs presenting substantially parallel plane surfaces facing one another and a base portion joining said legs, a link, each end of said link having substantially parallel plane surfaces on opposite sides of the link, and each end of said link extending between the legs of a respective attaching member with each of said end surfaces of said link in bearing relation with the plane surface of one of the legs of a respective attaching member, and detachable pivot means pivotally con-

necting respective ends of said link to the respective attaching members, each of said elements having the base portion thereof joining the legs slotted transversely to accommodate the link for pivotal movement thereof into said slotted portion between said legs, the slotted portions of said U-shaped elements being located at opposite sides of their respective attaching members, the attaching members being arranged with respect to the link so that when pivotally disposed with their base portions facing toward one another the unslotted base portion of one attaching member is disposed on one side of said link and the unslotted base portion of the other attaching member is disposed on the other side of said link, whereby to permit pivotal movement of said attaching members in the same direction relative said link, said link having a plurality of pin receiving apertures adjacent each end of said link, said apertures being disposed in spaced relation lengthwise of said link whereby said detachable pivot means may be selectively inserted through said apertures for adjusting the effective length of said link when the respective pivot members are operatively associated with the respective attaching members.
